UNITED STATES PATENT OFFICE.

DAVID S. FRENCH AND HAROLD S. FORSBERG, OF BRIDGEPORT, CONNECTICUT, AS-SIGNORS TO THE FORSBERG MANUFACTURING COMPANY, OF BRIDGEPORT, CONNECTICUT, A CORPORATION OF CONNECTICUT.

HINGE.

Application filed September 28, 1923. Serial No. 665,480.

To all whom it may concern:

Be it known that we, DAVID S. FRENCH and HAROLD S. FORSBERG, citizens of the United States, and residents of Bridgeport, 5 in the county of Fairfield and State of Connecticut, have invented certain new and useful Improvements in Hinges, of which the following is a specification.

This invention relates to a double acting 10 floor hinge and the object of the invention is to provide a hinge of the present character which will be an improvement generally upon all hinges of the same type heretofore known.

15 With the above and other objects in view, the invention comprises the construction, arrangement and combination of parts as now to be fully described and as hereinafter to be specifically claimed, it being understood 20 that the disclosure herein is merely illustrative of the principles of the invention and meant in no way in a limiting sense, changes in details of construction and arrangement of parts being permissible so long as within 25 the scope of the appended claims.

In the accompanying drawing forming a part of this specification,

Fig. 1 is an elevational view of the novel hinge shown as applied to use, the usual side 30 plates being omitted for the sake of clearness, disclosing a door, in connection with which the hinge is employed, in closed position;

Fig. 2 is a sectional view on line 2—2 in 35 Fig. 1, showing, in dotted lines, the hinge as in Fig. 1, and, in full lines, the hinge as when the door is thrown wide open;

Fig. 3 is a sectional view, on an enlarged 40 scale, as on line 3—3 in Fig. 2;

Fig. 4 is a sectional view, on the scale of 45 Figs. 1 and 2, on line 4—4 in Fig. 3; and

Fig. 5 is a sectional detail disclosing the 50 manner of adjusting the plunger.

The hinge of the present invention is 55 adapted for use in connection with doors designed to be swung wide open in two directions, and includes mechanism for maintaining the door in closed position, or in either wide open position.

50 With respect to the drawing and the numerals of reference indicated thereon, 10 denotes the hinge frame consisting of an upper plate 11 and a lower plate 12. As disclosed, the lower plate is bent adjacent its two ends,

as at 13, and said ends are secured to the upper plate in any manner, preferably so that the body of the plate 12 between the bends 13 is parallel with the plate 11. 14 represents an extension of the upper plate, beyond the preferably vertically disposed end 60 portion 15 of the lower plate, for a purpose to be made obvious.

Numeral 16 indicates a floor plate having holes to receive screws 17 for attaching the floor plate in position beneath a door, as indicated in Fig. 1. As disclosed, the floor plate has, preferably adjacent its center, a raised portion 18 providing a pocket 19 beneath said plate to receive a reinforcing block 20, and the raised portion and block 70 have square openings, denoted 21 and 22, respectively, to receive a squared end 23 of a stationary post 24, the squared end being permanently secured in the raised portion and block as indicated at 25.

As shown more clearly in Fig. 3, the lower plate 12 has an opening 26 rotatably and snugly receiving a cylindrical portion 27 of the stationary post situated a trifle above said raised portion, and 28 denotes a stop plate, fixed upon said squared end and located between the lower plate and raised portion of the floor plate, having oppositely disposed stops 29 adapted to be engaged by a pin 30 projecting downwardly from said 85 lower plate. See Fig. 4.

The stationary post 24 has oppositely disposed wings 31, situated above said stop plate and at some little distance from the upper plate of the frame, merging in vertically arranged, pivotal shoulders 32 against which a spring actuated plunger 33, to be described, operates. The stationary post also includes an annular, horizontally disposed plate member 34 situated at the top 90 of said post and beneath said upper plate 11.

Numeral 35 represents a cap rigidly secured to the upper plate 11, as by means of a rivet 36 arranged centrally of said cap, 100 just above the stationary post, the cap having a flange 37 providing a circumferential bearing surface 38 rotatably and snugly engaging the circumferential margin 39 of the annular, horizontal plate member 34. 105 The flange also provides a pocket 40 between the annular plate member and cap for the reception of balls 41 which are po-

sitioned in individual sockets 42 of a ball retaining member 43 secured in said cap in any suitable manner, the balls providing a bearing between the cap and the upper face 5 of the annular plate member. 44 is a stud projecting upwardly from the plate 11 which is, as shown, integral with the rivet 36, and 44' is a head on said stud for a purpose to be set forth.

10 The plunger 33 has a head forming a yoke 45 the spaced apart arms 46 of which are each provided with a vertically arranged, elongated groove 47 adapted to be entered by a pivotal shoulder 32 of the stationary post 15 24, the grooves, naturally, being made to correspond in shape and size with the bearing surfaces of said pivotal shoulders.

As more clearly shown in Figs. 1 and 2, the end of the plunger opposite its head is situated in an off center opening 48 in a disc 56 rotatably fitting the end portion 15 of the lower plate, which end portion lies between a bend 13 and the upper plate at farthest distance from the stationary post, to be freely slidable in said disc, there being a coil spring 49 on said plunger and engaging the yoke and disc 56 to normally hold the grooves of both of said yoke arms against the pivotal shoulders of the stationary post, as best shown by dotted lines in Fig. 2, and to insure the intended relation of the disc and end portion 15.

Numeral 59 represents an attaching plate to be secured to the bottom edge of a door 35 A in any suitable manner, as by screws 51, best disclosed in Fig. 1, the attaching plate having an elongated slot 52 including a wide and a narrow portion. As shown, the attaching plate is mortised in, and the door is 40 cut away as at 53.

To secure the hinge to a door, the head 44' of the stud 44 may first be inserted through the wide portion of the elongated slot 52, said wide portion being of sufficient width to this end, and may then be moved to the narrow portion of said slot, of insufficient width to allow passage of the head. A screw 54 may then be inserted in an opening in the extension 14 of the upper plate 50 of the frame and turned into the bottom edge of the door. See Fig. 1. The door is thus made ready to be set up.

An ordinary top pivot (not shown) is applied at the top of the door to function in cooperation with the novel hinge. When setting up the door with hinge attached, the top pivot may first be associated with the structure to receive the door in a manner which is obvious, and the floor plate of the hinge may afterwards be fastened down with the door in its normal (closed) position, as already described. Before the floor plate is fastened down, the door should be plumb and in line with the jamb. However, 55 the disc 56 with its opening 48 provides for

adjusting the door either before or after it is secured. To this end, the disc has peripheral ribs 57 providing slots 58 and the end portion 15 has a protuberance 59 to lie in any one of the slots between two ribs to 70 normally hold the disc from turning in the end portion, as will be understood. By inserting a suitable tool in one of the slots, the disc can be rotated, the coil spring receding against the action of the tool to allow the 75 protuberance to ride over the ribs, to move the outer end of the plunger 33 transversely of the door jamb.

The manner in which the hinge functions will be obvious from the drawing and full 80 description. It is shown in its normal position in Fig. 1. Here the door is closed and each of the pivotal shoulders 32 is resting in a groove 47 of an arm 46 of the yoke, the coil spring being sufficiently compressed to insure that the door will remain in closed position until it is intentionally opened. When force is exerted to open the door, the frame 10 of the hinge is swung upon the stationary post as a pivot. That is to say, the lower 90 plate 12 of the frame pivots on the cylindrical portion 27 of said post, while the cap 35 of the upper plate 11 pivots on the annular plate member 34 of said post, special 95 attention being directed to the fact that there is an ordinary ball bearing, as well as a circumferential bearing between said cap and annular plate member.

When the door is swung open in either direction the net result is the same, the pivotal shoulder and yoke arm with grooves, respectively, being duplicates of each other, except that in the case of each, one is right and one is left.

To open the door, as shown in Figs. 2, 105 3 and 4, sufficient force is applied to overcome the action of the coil spring. As the door opens, one of the yoke arms leaves its pivotal shoulder, as is obvious, and the other yoke arm turns on its pivotal shoulder to move the yoke and plunger away from the axis about which the hinge frame pivots, the plunger moving outwardly through the opening 48 in the position 15 of the lower member of the frame.

Naturally, the tendency of the coil spring is to urge the door toward closed position while the plunger is turned about the shoulder 32 as a pivot, until said plunger has reached its dead center position, but as soon as the plunger has passed the dead center position, the spring urges the door in opposite direction, toward wide open position, as will be apparent. But at this time, or soon after, the pin 30 on the lower plate 12 of the frame engages a stop 29 of the stop plate to arrest the opening movement of the door, and the door remains in stable, wide open position. To close the door, force is applied to move the frame 110 120 125 130

in reverse direction past the dead center position of the plunger as before. As disclosed, the door would be swung on an arc of about 90° from closed position to the dead center position of the plunger, the pin 30 engaging the stop 29 almost immediately after the dead center position is passed, whereby the door when open is at an angle slightly greater than a right-angle to the structure having the door, as is to be preferred.

Having thus fully described the invention, what we claim as new and desire to secure by Letters Patent is:

15 1. A hinge comprising a floor plate, a stationary post secured therein, said post including a cylindrical portion and having oppositely disposed pivotal shoulders, an annular plate member fixed upon said 20 pivotal shoulders and surrounding the post, a frame comprising an upper plate with cap pivotally associated with said annular plate member and a lower plate pivoted upon said cylindrical portion, the flange of said cap 25 engaging the circumferential margin of said annular plate member and there being a pocket between said annular plate member and cap, said post extending into said pocket, a ball retaining member in said 30 pocket and rotatable upon said post, said ball retaining member having individual sockets spaced from said post, balls in said

sockets and engaging the adjacent faces of said annular plate member and cap, a stop plate with stops, a pin on said lower plate 35 and adapted to engage said stops, and a spring actuated plunger associated with said frame and including arms with grooves adapted to engage said pivotal shoulders.

2. A hinge comprising a floor plate, a 40 stationary post secured therein, a frame pivoted upon the post and comprising an upper plate, a lower plate and a connector between said plates and spaced from the pivot for the frame, a spring actuated 45 plunger associated with the frame, means for adjusting the outer end of the plunger transversely of a door jamb, said means comprising a disc rotatably fitting the connector of the frame and having an off center 50 opening in which the plunger is slidably arranged, the disc extending beyond the frame connector and having peripheral ribs providing slots adapted to receive a tool 55 for rotating the disc, and a protuberance upon said connector and adapted to lie in any one of said slots of the disc between the ribs thereof to normally hold the disc from turning in the frame connector.

Signed at Bridgeport, in the county of 60 Fairfield, and State of Connecticut, this 14th day of August, A. D., 1923.

DAVID S. FRENCH.

HAROLD S. FORSBERG.
